UNITED STATES PATENT OFFICE.

SPEROS PANAGOPULOS, OF LISBON, OHIO.

FOLDING CHAIR.

Application filed July 7, 1924. Serial No. 724,644.

To all whom it may concern:

Be it known that I, SPEROS PANAGOPULOS, a citizen of the United States, residing at Lisbon, in the county of Columbiana and 5 State of Ohio, have invented certain new and useful Improvements in a Folding Chair, of which the following is a specification.

This invention relates to new and useful 10 improvements in chairs and is principally adapted to a child's chair which may be readily and easily folded when not in use and placed in a suitable casing to facilitate the carrying or storing away thereof.

15 Another important object of the invention is to provide a folding chair of the above mentioned character, wherein means is associated therewith for supporting the chair when in use.

20 A further object is to provide a child's folding chair which includes a means for supporting the same on the back of an ordinary chair, means being further provided for bracing the sides and back of 25 the chair when in use.

A further object of the invention is to provide a child's folding chair of the above mentioned character, which is simple in construction, inexpensive, strong and durable 30 and furthermore adapted for the purposes for which it is designated.

Other objects and advantages of this invention will become apparent during the 35 course of the following description.

25 In the accompanying drawing forming a part of this specification and in which like numerals designate like parts throughout the same:

Figure 1 is a perspective view of my improved chair showing the same in an assembled position.

Figure 2 is a bottom plan view thereof when in a folded position, and

40 Figure 3 is a side elevation of the case for receiving the folded chair.

In the drawing wherein for the purpose of illustration is shown the preferred embodiment of my invention, the numeral 1 designates the bottom of seat of my improved folding chair and the same is preferably formed of wood and is substantially rectangular in design. Extending across the bottom of the seat adjacent the side edges thereof are the rods 2 and 3 respectively, 45 the same being supported in position on the bottom of the seat through the medium of

the longitudinally extending strip 4. This construction is more clearly illustrated in Figure 2 of the drawing. The rods are adapted for swinging movement on the bottom 60 of the seat for the purposes hereinafter to be more fully described.

One end of each rod is disposed upwardly so as to extend substantially vertically with respect to the seat 1 when the parts are 65 assembled in the manner illustrated at 5 in the drawing. The ends of the upstanding portions 5 of the rods 2 and 3 terminate in the downwardly extending hooks 6 to provide a means for supporting the chair when the 70 same is in use, the hooks 6 being adapted to extend over the upper edge of the back of an ordinary chair (not shown). The opposite ends of the rods are also disposed upwardly so as to extend vertically in the front 75 of the seat in the manner illustrated at 7 for a suitable height and the rods are then disposed rearwardly in a plane substantially parallel to the seat as shown at 8 so that the horizontally extending portions of the rod 80 will engage the vertically extending portions 5 arranged in the rear of the seat 1 as is clearly illustrated in Figure 1. The ends of the rods are then disposed laterally as illustrated at 9 and thence upwardly as at 85 10 and terminate in the rearwardly curved portions 11 which engage the portions of the rods 5 adjacent the hooks 6. The upstanding portions 10 of the rods will be spaced from the portions 5 and extending across the 90 upstanding portion 10 and adapted to be detachably secured thereto is the back rest 12. In order to prevent the collapsing of the 95 chair, the brace 13 is provided and the same extends across the forward portions of the horizontally disposed portions 8 of the rods in the manner illustrated in Figure 1. This would tend to hold the rods in proper position when the chair is in use and when it is desired to fold the chair in order to store 100 the same away or to facilitate the carrying thereof from one place to another, the brace 13 and the back rest 12 may be readily disengaged from the rod and the rod may be folded in the manner as illustrated in Figure 105 2 on the under side of the seat 1. Handles 14 are provided on the horizontally disposed portions 8 to facilitate the lifting of the chair. When in a folded position, the chair may be readily inserted in 110 a suitable case such as is illustrated at 15 in Figure 3 of the drawing. When within

the case, the chair may be easily and efficiently carried from one place to another.

The provision of a child's folding chair of the character above described enables 5 the parts to be readily and easily assembled so that the chair may be placed in position on the back of an ordinary chair and when in such position, the child's feet may rest on the seat of the ordinary chair on which 10 the folding chair is supported. A device of the character above described will not only be inexpensive, but will also be strong and durable as well as easily and quickly assembled or disassembled.

15 While I have shown the preferred embodiment of my invention, it is to be understood that various changes in the size, shape and arrangement of parts may be resorted to without departing from the spirit of the invention and the scope of the appended 20 claim.

Having thus described the invention, what I claim is:—

A folding chair including a seat, a pair 25 of spaced parallel strips on the bottom surface of the seat, a pair of rods adapted for swinging movement between the bottom sur-

face of the seat and the strips, said rods extending transversely of the strips adjacent the sides of the seat, one end of each rod 30 being disposed upwardly so as to extend vertically from the rear portion of the seat, hooks formed on the upper ends of the aforementioned ends of said rods, providing supporting means for the chair, the 35 opposite end of each rod being disposed upwardly so as to extend vertically at the forward edge of the seat for a suitable distance, and then disposed rearwardly and engaging the aforementioned vertically extending portion at the rear edge of the seat, the end of each rod then being disposed laterally and upwardly and curved at its 40 end to engage the upper portion of the vertically extending portion of the rod at the rear of the seat, a back rest extending across the upwardly extending portion of the rods, at the rear of the seat, means for bracing the portions of the rods adjacent the forward edge of the seat, and handles 45 carried by the horizontally disposed portions of said rods.

In testimony whereof I affix my signature.

SPEROS PANAGOPULOS.
